UNITED STATES PATENT OFFICE

150,382

DESIGN FOR A REFRIGERATOR CABINET

Carl W. Sundberg and Montgomery Ferar, Detroit, Mich., assignors to Seeger-Sunbeam Corporation, St. Paul, Minn., a corporation of Minnesota

Application February 1, 1946, Serial No. 126,168

Term of patent 3½ years

(Cl. D67—3)

To all whom it may concern:

Be it known that we, Carl W. Sundberg and Montgomery Ferar, both citizens of the United States, and residents of Detroit, county of Wayne, and State of Michigan, have invented a new, original, and ornamental Design for a Refrigerator Cabinet, of which the following is a specification, reference being had to the accompanying drawing, forming a part thereof.

Figure 1 is a perspective view of a refrigerator cabinet, showing our new design;

Figure 2 is a top plan view of the same;

Figure 3 is a front elevational view of the same;

Figure 4 is a side elevational view of the same;

Figure 5 is a bottom plan view of the same; and

Figure 6 is an enlarged top view of the cabinet handle.

We claim:

The ornamental design for a refrigerator cabinet, as shown.

CARL W. SUNDBERG.
MONTGOMERY FERAR.
